(57) **CLAIM**

The ornamental design for a pot with removable rack, as shown and described.

DESCRIPTION

FIG. 1 is a front perspective view of a pot with removable rack in a closed configuration in accordance with the present design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is a front perspective exploded view thereof;

FIG. 9 is a further front perspective view of a pot with removable rack in a closed configuration in accordance with the present design;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof; and,

FIG. 16 is a front perspective exploded view thereof.

The broken lines shown are included for the purpose of illustrating a portion of the pot with removable rack that forms no part of the claimed design.

1 Claim, 14 Drawing Sheets
